UNITED STATES PATENT OFFICE.

EBERHARD FABER, OF WEST NEW BRIGITON, NEW YORK.

DESIGN FOR AN ERASER.

SPECIFICATION forming part of Design No. 23,473, dated July 17, 1894.

Application filed February 16, 1894. Serial No. 500,421. Term of patent 14 years.

To all whom it may concern:

Be it known that I, EBERHARD FABER, a citizen of the United States, and a resident of West New Brighton, in the county of Richmond and State of New York, have invented a new and original Design for India-Rubber Erasers, of which the following is a specification.

My design for rubber erasers is represented 10 in the accompanying drawings, in which—

Figure 1, is a plan or face view of a rubber eraser made according to my design. Fig. 2, is a right hand end view. Fig. 3, is a left hand end view, and Fig. 4, is an edge view.

15 In plan view my design for erasers presents a parallelogram with the corners rounded; two diagonally opposite corners being rounded on a larger curve than the other two. The said view also shows two margins of the figure 20 sloping downward to the edges, the other two margins presenting a level plane to the edges. The reverse side of the eraser is of like form, but the sloping margins of one side are opposite to the margins of the level plane of 25 the other side; *c* represents the flat part of a

side seen in plan view, *e* one bevel margin and *f* the other; *b* represents the corners formed on the larger curve, and *a*, the corners formed on the smaller curve.

In edge view and also in end view the form 30 of the eraser is rhomboidal; *d*, being the flat portion of the other side and *h* and *g*, being the bevel margins of the said other side.

My design differs from the geometric rhomboid in that it is made with six sides comprising two rhomboidal figures whereof two sides—*c* and *d*—are parts of both rhomboidal figures, and the corners are rounded. 35

I claim—

The design for rubber erasers as shown and 40 set forth.

In testimony that I claim the foregoing as my invention I have signed my name, in presence of two witnesses, this 14th day of February, 1894.

EBERHARD FABER.

Witnesses:

ALF. FORNANDER,
W. J. MORGAN.
